UNITED STATES PATENT OFFICE.

GARDNER L. CONLEY, OF CHICAGO, ILLINOIS, ASSIGNOR TO STANDARD OIL COMPANY,
OF WHITING, INDIANA, A CORPORATION OF INDIANA.

DISPLAY CONTAINER.

Application filed December 10, 1924. Serial No. 754,868.

To all whom it may concern:

Be it known that I, GARDNER L. CONLEY, a citizen of the United States, residing at Chicago, in the county of Cook and State 5 of Illinois, have invented a new and useful Improvement in Display Containers, of which the following is a specification.

The present invention relates to improvements in display containers, and will be 10 fully understood from the following description, illustrated by the accompanying drawings, in which:

Figure 1 is a perspective view of the container from the front, the container being 15 partly open;

Fig. 2 is a detailed sectional view on the line 2 of Fig. 2; and

Fig. 3 is a detailed sectional view on the line 3 of Fig. 1.

The carton or display case of the present invention is particularly intended for the display of individual articles, such as candles, and is intended to provide a secure container for the candles to be displayed, 25 as well as means for facilitating their display in association with one another without handling.

As will be readily seen from the drawing, the display container is of box-like 30 form as shown at 5, completely closed except upon one side (the front, as shown in the drawing), and the top. A plurality of transverse partitions 6 are provided, and one or more vertical partitions 7 may also 35 be provided, thereby forming a plurality of compartments open at the front only, and upper compartments open both at front and on top. Longitudinally partitioned drawers 8 are fitted in the last 40 named compartments, and similar drawers 9 are fitted in the other compartments. The longitudinal partitions in these drawers, all of which are open at the top, form individual compartments for the candles 11 to be 45 displayed. The drawers 8 and 9 are of such size that, when fully inserted, they are flush with the front of the container 5.

To the front of the box 5 a flap 12 is 50 hingedly secured by means of a strip of flexible material which may suitably be of fabric or paper. The mating edges of the

flap 12 and of the bottom of the box 5 are suitably mitered or otherwise disposed so that the flap 12 may be raised, as shown in dotted lines in Fig. 2, to lie against the 55 front surface of the box 5. The sides of the box 5 are provided externally with a reinforcing sheet 5^a, and the flap 12 with a similar reinforcing sheet 12^a, these reinforcing pieces extending upwardly from the 60 bottom of the box for equal distances. Hingedly secured to the back of the container 5 is provided a box-like cover 14, which may be closed down. When so closed, its lower edge rests upon the upper 65 edge of the reinforcing strips 5^a and 12^a.

The individual compartments in the drawers 8 and 9 formed by the longitudinal partitions 10 are of such size that each 70 securely holds a candle 11. The candles in the several drawers are preferably grouped together; for example, all of the candles in drawer 8 may be of the same general style in varying color effects, and similarly for the candles in the other drawers. A 75 complete display for all of the candles may be effected by raising the cover 14, opening the flap 12, and partially pulling out the drawers 9, as shown for one side of the carton in Fig. 1. By completely closing 80 the container, the candles are securely protected.

As shown in Fig. 1 of the drawing, the upper portion of the sides and back of the container are of relatively greater thickness 85 than the remainder of the structure, thus adding to its strength and preventing buckling intermediate its ends when being carried in filled condition. In addition, these 90 portions afford a ledge-like appearance and add to the attractiveness of the display structure as a whole.

I claim:

A display container for candles of box-like form with an open top, reinforcing strips extending partly up the sides of the container, partitions extending horizontally and vertically of the container and forming compartments therein, drawers slideable 95 in said compartments, the top tier of said drawers being partitioned to form compartments for the individual articles to be dis- 100

played, a cover hingedly secured to the box and having depending sides adapted to rest on the reinforcing strips on the sides of the box when the cover is closed, a front-forming member hinged to the bottom of the box and adapted to be turned up to close the front of the box with its outer free edge extending within the cover when the latter

is closed, those portions of the upper side edges and the rear of the box being of relatively greater thickness than the remainder of the body of the box whereby to give increased strength to the structure and to enhance the attractiveness of the display. 10

GARDNER, L. CONLEY.
